Edgar F. Allen.

UNITED STATES PATENT OFFICE.

ARVID F. CARLIN, OF NEW YORK, N. Y.

MECHANICAL FAN.

1,135,257.

Specification of Letters Patent. Patented Apr. 13, 1915.

Original application filed December 26, 1912, Serial No. 738,539. Divided and this application filed December 9, 1913. Serial No. 805,491.

To all whom it may concern:

Be it known that I, ARVID F. CARLIN, a citizen of the United States, and residing at New York, in the county of New York 5 and State of New York, have invented certain new and useful Improvements in Mechanical Fans, of which the following is a specification, such as will enable those skilled in the art to which it appertains to make and 10 use the same.

This invention relates to mechanical fans, and the object thereof is to provide an improved device of this class which may be secured to a vertical support of any kind and 15 turned or adjusted into different positions and be operated by a cord suspended therefrom for the convenience and comfort of a person sitting in a chair adjacent to the support, and with these and other objects in 20 view, the invention consists in a device of the class specified constructed and operating as hereinafter described and claimed.

The invention described and claimed herein is an improvement on that described and 25 claimed in a prior application for Letters Patent of the United States filed by me December 26, 1912, Serial No. 738,539.

The present invention is fully disclosed in 30 the following specification, of which the accompanying drawing forms a part, in which the separate parts of my improvement are designated by suitable reference characters in each of the views, and in which—

Figure 1 is a sectional side view of my improved fan device and showing the same connected with a vertical support;—Fig. 2 a 35 partial section on the line 2—2 of Fig. 1 with parts broken away, and;—Fig. 3 a view similar to Fig. 1, but showing only parts of 40 the construction, and showing said parts on an enlarged scale.

In the practice of my invention, as shown 45 in the drawing, I provide a suitable box or casing *a* the back of which is provided with a raised attaching member *a*² forming part of the means for securing the fan to a vertical support, and the bottom of the casing *a* is provided with an oblong slot or opening *a*⁴.

In the back part of the casing *a* are two 50 vertical partition plates *a*⁵ and *a*⁶ forming a spring chamber *a*⁷ and a back chamber *a*⁸, and mounted centrally and longitudinally in said casing, and passing through the 55 chamber *a*⁷ is a shaft *b* which projects

through the front partition plate *a*⁵, and into the chamber *a*⁸, and a plate spring *b*² is secured in the bottom of said chamber and bears on the end of the shaft *b*, and said shaft is longitudinally movable to a slight extent. 60

Mounted on the shaft *b* within the main compartment *a*¹⁰ of the casing *a* and secured to said shaft is a drum *c*. The drum *c* may be secured to the shaft *b* by solder, as shown 65 at *c*², or in any other way, and secured to one end portion of said drum and wound therein is a cord *d* one end portion *d*² of which is passed out through the slot or opening *a*⁴.

Mounted on the front end portion of the 70 shaft *b* adjacent to the front wall *a*⁹ of the casing *a* is a gear wheel *e* the inner side of which is provided with a ratchet *f* which is secured thereto and provided with teeth on its inner face, and secured to the shaft *b* 75 between the ratchet *f* and the corresponding end of the drum *c* is a radial pawl *g* having a nose which operates in connection with the teeth of the ratchet *f*.

Within the spring chamber *a*⁷ is placed a 80 strong helical spring *h* one end of which is secured to the casing *a*, and the other to the shaft *b*, and mounted in the bottom part of the front wall *a*⁹ of the casing *a* is a fan shaft *i*, the inner end of which is provided 85 with a pinion *i*² which meshes with the gear *e* on the shaft *b*, and the other end of the shaft *i* is provided with a fan *j*.

In the use of my improved fan device, it is 90 connected with a vertical support *k* of any kind or class and to which is secured a curved arm *k*² provided with a longitudinal slot *k*³, and the attaching member *a*² at the top of the casing *a* is provided with a flat foot piece *m* through which is passed a 95 screw *m*² provided with a thumb nut *m*³.

The back of the casing *a* is also provided with a downwardly directed attaching member *n*, and secured to the support *k* is a bracket plate *o* having an outwardly directed 100 and curved top piece *o*² provided with an opening *o*³, and the attaching member *n* is provided at its end with a neck *a*⁴ which is passed through the opening *o*³ and provided with a head or nut *o*⁵, and by means of this 105 construction, the fan device may be moved outward or from the support *k* and adjusted in any desired position between that shown in full lines in Fig. 1, and that shown in dotted lines, and the fan device may be also 110

rotated laterally or in the direction of the arrows x and x^2 in Fig. 2, and adjusted laterally into different positions.

The plate o , in the form of construction shown, is secured to the support h by an eye screw p with which is connected a guide pulley, or similar device, p^2 , and the end d^2 of the cord d is passed through said guide pulley and may be manipulated for the purpose of operating the fan j by a person sitting or standing adjacent thereto.

In the construction shown, the fan j is mounted parallel with the front of the casing a , but my invention is not limited to this relative location of said fan, and said fan may be placed in any desired position, and changes in and modifications of the other features of construction herein shown and described may be made, within the scope of the appended claim, without departing from the spirit of my invention or sacrificing its advantages.

It will be understood, that a pull on the end d^2 of the cord d will turn the drum c in one direction, and the fan j in a corresponding direction, and this pull on the cord d winds up the spring h , and when said pull is released, the spring h will turn the drum c and the fan j in opposite direction, and in this way, the fan j may be continuously operated by intermittent pulls on the cord d , or the end d^2 thereof.

It will also be seen that as the drum c is operated, there is a continuous oscillating or vibratory movement of said drum and the shaft b , said drum and shaft being moved

in one direction by the pawl g passing over the teeth of the ratchet f , and in the other direction by the spring b^2 .

It will also be seen that the adjustment of the fan device toward and from the support h involves the idea of holding said fan device at a downward inclination to said support, which results from the fact that the connection of the bottom attaching member n with the plate o , or the part o^2 thereof, has but little, if any, movement toward and from the support h , while the connection of said fan device with the arm h^2 permits of considerable movement of said device toward and from said support.

Having fully described my invention what I claim as new and desire to secure by Letters Patent is:—

In an apparatus of the class described, a support, a slotted arm connected with said support and projecting therefrom, a bracket secured to said support below said arm, and a fan casing the back of which is provided with a top attaching member slidably and rotatably connected with said arm and the bottom of which is provided with an attaching member rotatably connected with said bracket.

In testimony that I claim the foregoing as my invention I have signed my name in presence of the subscribing witnesses this, 6th day of December 1913.

ARVID F. CARLIN.
